UNITED STATES PATENT OFFICE

96,700

DESIGN FOR A REFRIGERATOR CABINET

Judson S. Sayre, Chicago, Ill., assignor to Montgomery Ward & Co., Incorporated, Chicago, Ill., a corporation of Illinois

Application May 5, 1934, Serial No. 51,701

Term of patent 3½ years

To all whom it may concern:

Be it known that I, Judson S. Sayre, a citizen of the United States, residing at Chicago, in the county of Cook and State of Illinois, have invented a new, original, and ornamental Design for a Refrigerator Cabinet, of which the following is a specification, reference being had to the accompanying drawing, forming a part thereof.

In the drawing,

The figure is a perspective view of a refrigerator cabinet showing my new design.

My design for refrigerator cabinet is characterized by the raised central portion of the top, the forward edge of which curves downwardly so as to present the appearance of a pendant apron the lower horizontal edge of which lies in parallel relation to the upper edge of the door. At each end of this raised central portion is formed a stepped or terraced capital or head for the side panel of

the cabinet therebeneath. This is constituted by the end of the top merging by a downwardly-curved surface into an intermediate portion that lies in a lower plane than said end. The intermediate portion merges into a convex portion which lies in a still lower plane and, in turn, merges into the surface of the end panel of the cabinet.

My design is characterized further by the end panels being continuous unbroken surfaces from their top edges to the bottom edges of the base, with a projecting or offset horizontal bead arranged at the top of the base and extending around the cabinet at this point.

I claim:

The ornamental design for a refrigerator cabinet, substantially as shown and described.

JUDSON S. SAYRE.
